(57) CLAIM

The ornamental design for a bakeware, as shown and described.

DESCRIPTION

FIG. 1 is an exploded perspective view of a bakeware showing the claimed design;

FIG. 3 is an exploded front elevational view thereof;

FIG. 4 is an exploded right side elevational view thereof;

FIG. 5 is an exploded rear elevational view thereof;

FIG. 6 is an exploded left side elevational view thereof; and,

FIG. 7 is a bottom plan view thereof.

The broken lines illustrate portions of the bakeware that form no part of the claimed design.
